INVENTOR,
John J. Stanford,
BY
Harry W. Bowen,
ATTORNEY.

UNITED STATES PATENT OFFICE

JOHN J. STANFORD, OF SPRINGFIELD, MASSACHUSETTS

NAIL SET

Application filed April 11, 1931. Serial No. 529,321.

My invention relates to improvements in nail sets.

An object of my invention is to provide a nail set which may be readily adjusted, in order to positively retain the nail set over the head of a nail, in one of its adjusted positions, or, to set the nail head below the surface of the material into which the nail is being driven, in its other adjusted position. This and other objects and advantages of my invention will appear in the specification, with reference to the accompanying drawings, and appended claims.

Broadly, my invention comprises a tubular body member, a centrally or axially arranged slidable shaft which is the nail set proper, and means co-operating between these members for changing their relative positions, so that in one position the point of the central member is enclosed within and above the nose or lower end portion of the body member, thus forming a socket into which the head of a nail may be inserted and retained, and, in the other position, the point or lower end of the central member which engages the head of a nail will project a predetermined distance beyond the nose or lower end of the body member, thus permitting the head of the nail to be driven below the surface of the material into which the nail is being driven until the nose or lower end of the body member rests upon the surface of the material, as wood, as will more fully appear.

A preferred form of my invention is illustrated in the accompanying drawings, in which:

Fig. 1 is an elevational view of the assembled nail set showing the shaft in its elevated or retracted position.

Fig. 2 is a sectional view through the axis of the nail set showing the shaft of the nail set adjusted or elevated to retain a nail head within the nose of the body portion.

Fig. 3 is a view similar to Fig. 2 showing the shaft of the nail set adjusted to set the head of a nail below the surface.

Fig. 4 is a sectional view on the line 4-4 of Fig. 2, looking in the direction of the arrows, and

Fig. 5 is a perspective view of the adjusting sleeve which controls the relative positions of the body member and the central or shaft member, and Fig. 6 is a modification of the attaching means of the sleeve.

Referring now to the drawings in detail, in which like numerals refer to like parts throughout:

The tubular body member 1, formed with the tapered nose or end portion 2, is bored out to form the cavity 3 and the bearing 4. The adjusting sleeve 5 is formed with the annular flange or shoulder portion 6, the bore 7 extending through the same and with the slots 8 and 9 and is secured in the upper end of the cavity 3 by the pin 10 engaging the bayonet slot 11 in the wall of the body portion 1. The slideable central member or shaft 12, formed with the square head 13, the integral shoulder or flange portion 14 and the reduced end 15, terminating in the set end 16 which is slightly concave to fit the head of a nail 17, is slidably secured and guided within the bore 7 of the sleeve 5 and the bearing 4 of the body member 1. The pin 18, (see Fig. 4), secured to the central slideable shaft member 12, engages either one of the slots 8 or 9, as the case may be, and thus retains the desired axial relation between the body member and the central shaft member. The compression spring 19 is guided in the cavity 3 and acting between the shoulder 20 formed in the body member 1, and the shoulder 14 on the central member 12, serves to maintain engagement of the pin 18 in either one of the slots 8 or 9 in the sleeve 5. The slots 8 are relatively deeper than the slots 9, thus the relative positions of the end 16 and the end 21 of the nose 2 or lower end is changed, depending upon which of the slots 8 and 9 is engaged with the pin 18.

The exterior surface of the body member 1 is knurled at 22 to facilitate the relative adjustment of the body member 1 on the central member 12.

In operation, the body member 1 is first moved upward against the action of the spring 19 until the pin 18 is released from engagement with the short slots 9 in the

sleeve 5, then rotated or turned about 90° until the pin 18 engages or registers with the longer slots 8. In this position, the end 16 of the central member 12 is retracted or retained within the bearing 4 and above the lower end 21 of the nose 2, as indicated in Fig. 2. In this position, the nose 2 may be set down over the head 17 of a nail 17¹, and the nail set is effectually prevented from slipping off the head of the nail while the latter is being driven by striking the upper end 13. When the nail has been driven until the head is ready to be set, the pin 18 is released as before, and the body member 1 given a quarter turn about the central member 12, at which time the pin 18 will be engaged in the shorter slots 9. In this position, the end 16 projects beyond the nose 2, as indicated in Fig. 3, sufficiently to permit the head of the nail to be set below the surface of the material 19 into which it is driven.

Referring to the construction shown in Fig. 6 in which the sleeve 5, instead of being attached to the tubular member 1 with the pin 10 and slot 11, I preferably employ the threads 23 on the sleeve which engage the threads 24 on the inner upper end of the tubular member. This construction is preferable, as it avoids any possible loose connection between the sleeve and the tubular member. The flange 6 will then rest firmly on the upper end of the tubular member 1.

What I claim is:

35 1. In a nail set the combination, of a tubular member, a shaft slidably therein, means for retaining the shaft with its lower end retracted within the tubular member or projecting therefrom, said means comprising a slotted sleeve member located within the tubular member and through which the shaft extends and slides, a pin on the shaft, the slots of the sleeve being of unequal length and engageable by the pin when the shaft or sleeve is turned, and spring means for retaining the pin in the slots.

40 2. A nail set having in combination, a shouldered tubular member, a shouldered shaft slidably mounted in the tubular member, a spring engaging the said shoulders, a sleeve secured in the tubular member and formed with slots of unequal length and through which sleeve the said shaft slides, and co-operating means between the slots of the sleeve and the shaft for retaining the lower end of the shaft retracted into or extending from the tubular member, for the purpose described.

45 3. A nail set having in combination, a shouldered tubular member, a shouldered shaft slidably mounted in the tubular member, a spring engaging the said shoulders, a slotted sleeve secured in the tubular member and through which the said shaft slides, and co-operating means between the slots of the

sleeve and the shaft for retaining the lower end of the shaft retracted into or extending from the tubular member for the purpose described, said co-operating means comprising a pin on the shaft which engages slots of different lengths in the slotted sleeve. 70

4. A nail set comprising in combination, a member having an opening of different sizes extending through the same, a slideable shaft having a reduced end located in the smaller opening at one end of the tubular member, a sleeve having slots of unequal length secured in the other or opposite end of the said member and in which the shaft slides, a pin on the shaft for engaging the said slots of the sleeve, spring means for retaining the reduced end of the shaft extended or retracted into the smaller opening at its lower end for providing a recess to receive the head of a nail when the shaft is retracted or for engaging the head of a nail by the extended end of the shaft when the shaft is extended. 75

5. A nail set having in combination, a shouldered tubular member, a shouldered shaft slidably mounted in the tubular member, a spring engaging the said shoulders, a slotted sleeve having a threaded connection with tubular member and through which the said shaft slides, and co-operating means 90 between the slots of the sleeve and the shaft for retaining the lower end of the shaft retracted into or extending from the tubular member, for the purpose described. 95
